UNITED STATES PATENT OFFICE.

EMIL BEYER, OF NEWARK, NEW JERSEY.

IMPLEMENT FOR REMOVING JAR TOPS.

Application filed July 27, 1920. Serial No. 399,358.

To all whom it may concern:

Be it known that I, EMIL BEYER, a citizen of the United States, residing at Newark, in the county of Essex and State of New Jersey, have invented certain new and useful Improvements in Implements for Removing Jar Tops; and I do hereby declare the following to be a full, clear, and exact description of the invention, such as will enable others skilled in the art to which it pertains to make and use the same, reference being had to the accompanying drawings, and to characters of reference marked thereon, which form a part of this specification.

This invention relates, generally, to improvements in jar-openers; and, the present invention has reference, more particularly, to a novel construction of household article, in the form of an implement or tool, comprising a handle, adapted for use as a lever, and a flexible loop of thin piano wire, or the like, which is adapted to be placed either beneath or above the annularly projecting portions of the usual rubber sealing ring arranged about the neck of the jar and its hermetically sealed glass-top or cover, and by means of the handle the thin wire-loop is readily forced either between the lower surface of the rubber and the neck-portion of the jar upon which the rubber is placed, or between the upper surface of the rubber and the sealed glass-top or cover, so that without any twisting or rotary action of the wire-loop and without damage to the rubber, an air-induction space or opening is produced to permit an inrush of air into the body of the jar, and whereby the usual and previously tightly sealed glass-top or cover can be readily lifted without force from such previously sealed position upon the top-opening or mouth of the jar.

With the above-stated purposes in view, the said invention has for its principal object to provide a novel and simply constructed sealing-cap or cover separating implement or tool for lifting and for the removal without any undue exertion of force or power of the usual sealing ring and glass-top or cover from the jar, and of the general character hereinafter more fully set forth.

Other objects of the present invention not at this time more particularly enumerated will be clearly understood from the following detailed description of the present invention.

The invention consists, therefore, in the

novel and simply constructed, as well as efficiently operating tool or implement herein-after more fully described, for the removal from a glass jar of the usual sealing rubber and the usual glass-top or cover.

The invention is clearly illustrated in the accompanying drawings, in which:—

Fig. 1 is a top or plan view of the usual glass-top or cover and a plan view of the separating and removing tool or implement, the top or cover being represented in its sealed relation upon the open top of a glass jar, and the separating and removing tool or implement being shown with its piano-wire loop inserted beneath the glass-top or cover, with the handle of the tool about to be operated for the separation of the sealing rubber and the glass-top or cover from their sealed relation with the jar.

Fig. 2 is a top-plan view of the separating and removing tool or implement, detached from the jar; Fig. 3 is a bottom plan view of the handle thereof, showing in connection therewith, fragmentary portions of the wire-loop; and Fig. 4 is a vertical sectional representation of the tool, said section being taken on line 4—4 in said Fig. 2, looking in the direction of the arrow *x*.

Fig. 5 is a top-plan view of a sealing-rubber and glass-top separating and removing tool of a slightly modified construction; Fig. 6 is a bottom-plan view of the same; and Fig. 7 is a longitudinal vertical sectional representation of the tool, said section being taken on line 7—7 in said Fig. 6, looking in the direction of the arrow *y*.

Similar characters of reference are employed in all of the said above described views, to indicate corresponding parts.

Referring now to Figures 1, 2 and 3 of the drawings, the reference-character 1 indicates a suitably shaped handle made from a blank of sheet-steel, or other suitable material, the said blank being provided at its one end with oppositely projecting horns, as 2 and 3, which are respectively formed with suitably disposed holes or perforations 4 and 5, that portion of the handle located between the said horns 2 and 3, being bounded by the concave marginal edge-portion 6, substantially as shown. The said handle being made of a thin metal, preferably of sheet-steel as has been stated, for strength and to prevent sharp marginal edge-portions, is preferably bounded by a marginal flange or rib, as 7, or other similar project-

ing member, as shown more particularly in Fig. 3 of the drawings.

The previously mentioned wire loop for separating the sealing ring or rubber 8, indicated in dotted outline in said Fig. 1, from the usual glass-top or cover 9 of the jar, is represented by the reference-character 10, said loop being preferably a piece of thin and flexible piano-wire. The ends 11 and 12 of said loop are inserted in the respective holes or perforations 4 and 5, and are twisted about the main wire of the loop, as at 13, 13, and as clearly shown in the several figures of the drawings.

Of course it will be understood, that the ends of the loop 10 may be otherwise connected with or secured to the respective horns of the handle, and I therefore do not limit myself to the exact manner of attaching the ends of the loop to the said horns 2 and 3, as represented in said Figures 1, 2, 3 and 4 of the drawings.

Referring now to Figures 5, 6 and 7 of the drawings, in which I have shown a slightly modified construction of sealing-rubber and glass-top separating and removing tool, the reference-character 14 indicates a suitably formed handle, preferably made of sheet-steel, or the like, the end-portion 15 of said handle being formed with oppositely projecting horns 16 and 17, and with the concave marginal edge 18, substantially as shown in Figure 5. The said horns 16 and 17 are also respectively provided with slits, 35 as 19, and back of said slits with marginal ears or lugs, as 20 and 21.

Mounted upon the lower face of the said end-portion 15 of the handle is an arc-shaped plate 22 formed with the concave marginal edge 23 which corresponds to the concave marginal edge 18 above-mentioned. The said plate 22 is also provided with the marginal ears or lugs 24 and 25 which are inserted through the said slits 18 and 19 for the purpose of securing the said plate 22 upon said end-portion 15 of the handle 14. The said plate 22 is also provided near its ends with perforations 26 into and through which are passed the ends of a wire loop 27, 50 said ends of the wire being bent over, as at 28, see Fig. 7, and being secured against displacement by the lugs or ears 20 and 21 which are bent over as shown, and are forcibly pressed down upon the bent over ends 55 28 of the wire loop 27, all of which will be clearly understood from an inspection of said Figures 5, 6 and 7 of the drawings.

When it is desired to use either of the tools or implements herein-above described 60 for separating the usual rubber ring and glass-top or cover from their hermetically sealed relation with the mouth of the usual glass preserving jar, the wire loop or bail 29 forming part of the jar is first disengaged 65 from its retaining engagement with the top

or cover, and the thin wire loop of the tool is then placed over the said top or cover and disposed either upon the upper projecting surface-portion of the sealing rubber or ring and beneath the corresponding portion of the glass-top or cover, or directly beneath the lower surface-portion of the said sealing rubber or ring, where it rests upon the corresponding portion of the jar, with the concave portion of the handle correspondingly placed against the side of the jar. By pulling laterally upon the handle, so as to use one of the projecting horns as a fulcrum, see Fig. 1 of the drawings, the thin wire loop is caused to cut in between the rubber and the glass-cover, or between the rubber and the body of the jar, as the case may be, thereby, at a portion of the jar opposite the fulcrumal point of the handle, disengaging the rubber sufficiently from its sealing relation with the cover of the jar, to provide an opening or space which permits of an inrush of air into the interior of the jar, and thereby enabling the operator to easily lift the cover from its previously closed and sealed relation with the jar, as will be clearly evident.

From an inspection of Fig. 1 of the drawings, it will readily be understood that in operating the handle, so that the latter will act in the manner of a lever, there is no twisting effect of the wire loop upon the rubber, so that there will be no tearing or crushing of the parts, which would otherwise render them inoperative for future use.

Of course, I am aware that some changes 100 may be made in the general form and proportion of the various parts, as well as in the manner of attaching or connecting the wire loop to the handle, without departing from the scope of the present invention. 105 Hence, I do not limit my present invention to the general arrangements and combinations of the several parts as particularly described in the foregoing specification, nor do I confine myself to the exact details of 110 the construction of the said parts, as illustrated in the accompanying drawings.

I claim:

1. A tool or implement adapted for use as a separator for the sealing rubber and glass top of a jar, comprising a handle and horns at one end of the handle, said horns extending laterally from the opposite and longitudinally extending marginal edge portions of the handle, and a thin wire loop attached at its respective ends to said horns, and at points upon the horns located beyond the longitudinally extending marginal edge portions of said handle, one of said horns serving as a fulcrum against the neck of the 125 jar, and the other horn serving as a pull-member and being adapted to be moved away from the neck of the jar when the handle is operated, so as to force the wire-loop either above or below the sealing rub- 130

ber to provide an air-induction space for lifting the glass top from the jar.

2. A tool or implement adapted for use as a separator for the sealing rubber and glass top of a jar, comprising a handle and horns at one end of the handle, said horns extending laterally from the opposite and longitudinally extending marginal edge-portions of the handle, and a thin wire loop attached 5 to its respective ends to said horns, and at points upon the horns located beyond the longitudinally extending marginal edge-portions of said handle, one of said horns serving as a fulcrum against the neck of the jar, and the other horn serving as a pull-member and being adapted to be moved away from the neck of the jar when the handle is operated, so as to force the wire-loop either above or below the sealing rubber to provide 10 an air-induction space for lifting the glass top from the jar, and a marginal re-enforcing rib surrounding said handle.
3. A tool or implement adapted for use as a separator for the sealing rubber and glass top of a jar, comprising a handle and horns at one end of the handle, said horns extending laterally from the opposite and longitudinally extending marginal edge-portions of the handle, a plate mounted upon 15 said horns and the connecting end-portion of the handle, means connected with said horns and said plate for securing the latter in a fixed position, and a thin wire loop attached at its respective ends by means of 20 said plate to said horns, and at points upon said horns located beyond the longitudinally extending marginal edge-portions of said handle, one of said horns serving as a fulcrum against the neck of the jar, and the other horn serving as a pull-member and being adapted to be moved away from the 25 neck of the jar when the handle is operated, so as to force the wire-loop either above or below the sealing rubber to provide an air-induction space for lifting the glass top from the jar.
4. A tool or implement adapted for use as a separator for the sealing rubber and glass top of a jar, comprising a handle and horns at one end of the handle, said horns extending laterally from the opposite and longitudinally extending marginal edge-portions of the handle, a plate mounted upon 30 said horns and the connecting end-portion of the handle, said horns being provided with slits and marginal ears extending from said plate into and through said slits and bent over upon said horns, a thin wire loop attached at its respective ends by means of 35 said plate to said horns, and at points upon said horns located beyond the longitudinally extending marginal edge-portions of said handle, and marginal lugs extending from said horns and bent over upon said plate to secure the fastened ends of said wire-loop against displacement, one of said horns serving as a fulcrum against the neck of the jar, and the other horn serving as a pull-member and being adapted to be moved away from the 40 neck of the jar when the handle is operated, so as to force the wire-loop either above or below the sealing rubber to provide an air-induction space for lifting the glass top from the jar.

In testimony, that I claim the invention set forth above I have hereunto set my hand this 24th day of July, 1920.

EMIL BEYER.
